UNITED STATES PATENT OFFICE.

FRANK A. HOWARD, OF ELIZABETH, NEW JERSEY, ASSIGNOR TO STANDARD DEVELOPMENT COMPANY, A CORPORATION OF DELAWARE.

ART OF CONTINUOUS DISTILLATION OF PETROLEUM OILS.

Application filed September 1, 1921. Serial No. 497,529.

The present invention relates to the art of continuous distillation of crude oils and will be fully understood from the following description thereof, illustrated by the accompanying drawings, in which:

Figure 1 is a sectional view showing a part of a battery of stills suitable for carrying out the invention;

Fig. 2 is a longitudinal sectional view 10 through a still of the battery on line 2 of Fig. 1; and

Fig. 3 is a transverse sectional view of a still on the line 3 of Fig. 2.

Referring more particularly to the drawings, the numeral 5 indicates a setting, fired by any suitable means, in which are mounted a plurality of lengths of pipes or tubes 6 forming a continuous coil. The connections between these lengths of pipes are preferably formed externally of the setting as indicated at 7 and the ends of the pipes are capped, as indicated at 8, the caps being removable for cleaning the interior of the pipes. Oil is introduced into the coil 25 through a suitable valved pipe 9 by any suitable means, for example a pump (not shown). It is preferably introduced into the portion of the coil in the lower and more highly heated portion of the setting and in 30 traveling through the coil passes upwardly through the setting. The oil passes out of the coil through pipe 10 and enters the upper portion of the enlarged chamber or drum 11, which is preferably mounted in the upper and less highly heated portion of the 35 setting. The hot combustion gases first play about the coil and afterwards pass to and by their residual heat, impart the desired temperature to the oil in the drum. The oil enters the drum 11 above the inclined plate or baffle 12, down which it flows. This plate feeds the incoming oil onto a second inclined baffle or plate 13, and this in turn feeds the oil upon the plate 14 from which it flows 40 into the body of the drum. The plates 12, 13 and 14 are alternately secured to opposite ends of the drum and are inclined in opposite directions, whereby the incoming oil is forced to travel in a tortuous path before 45 it reaches the body of the drum. At its top the drum is provided with a vapor outlet pipe 15 and at its bottom with a discharge pipe 16 for removing tars or bottoms. It is 50 apparent that the outgoing vapors are forced by the baffle plates 12, 13 and 14 to travel in

a tortuous path in counter-current to the oil before making their exit through the vapor pipe 15. It is readily apparent that the pipe 10 and the drum 11 may, if desired, be lagged. Furthermore, although three of the 55 baffle plates 12, 13 and 14 have been illustrated, more or less than this number may be provided if desired.

In Fig. 1 a number of stills of the character described are so arranged that the tars 60 or bottoms withdrawn from each still may be charged into the next in the same manner as the oil is charged into the still described. Thus, the pump 17 forces the residues issuing from drum 11 into the coil pipes 6^a 70 mounted in setting 5^a, and from this coil they enter drum 11^a, which is substantially identical in construction with drum 11. Vapors leave drum 11^a through vapor line 15^a and residues are discharged through the 75 line 16^a, to be forced into the next still of the series. If desired, a number of these stills may be arranged in the battery, the oil being fed progressively through the battery.

The respective stills may be provided with the usual condenser equipment (not shown), which may be arranged in the customary manner for the separation of the condensates from each still into light, intermediate 80 and heavy products.

An inert gaseous material, preferably steam, may be introduced into the stills in any suitable manner, for example, it may be introduced as steam or as water into the 85 charging pipe 9 through the valved connection 18, similar connections for the introduction of steam or water being provided for each still of the battery. It is likewise readily apparent that an inert gaseous material, preferably steam may be directly introduced into the drums by the means usual in the art for that purpose, such as perforated steam pipes 20 or the like.

In order that the present invention may 100 be fully understood it will be described in connection with the running of a crude oil, for example an oil of the character of West Colombia crude, having a density of about 23.3 Baumé. In the running of this oil the 105 stills of the battery were maintained under a vacuum of about 28 inches.

The oil is forced through the coil of the initial still at a rapid rate and enters drum 11 at a temperature of about 570° F., which 110

temperature is substantially maintained therein. Steam is likewise introduced, the proportion of steam being from 8 to 10% by volume (measured as condensed water) upon the charge. Approximately 47.3% of distillate is obtained, the bottoms or residue forming approximately 51.6% and having a gravity of about 19.7 Baumé. This residue is forced into the second still, about 10 to 15% of steam, measured as condensed water, being supplied therein. The temperature of the oil in the drum of the second still is approximately 580° F. From the second still the total distillate recovered amounts to about 12% of the crude treated and the residue to about 38.5%, having a gravity of 18.3° Baumé. This residue is charged into the next still and the operation is continued in a like manner through the successive stills of the battery, the residue from each still being charged into the next still of the series. The temperature to which the oil is subjected gradually increases as it travels through the series of stills and likewise the proportion of steam added may be increased in each still.

The temperature attained by the oil in the coil is higher than the temperature of the oil in the corresponding drum, the lowering in temperature being possibly due, at least in part, to the vaporization of the oil on entering the drum or in the pipe opening into the drum. Thus in the example given, the oil in the pipe coil of the first still attains a temperature of 600° F. or even somewhat higher, and on entering the drum the temperature is reduced to 570° F., for example, as stated in connection with the first still of the battery. This temperature is substantially maintained in the drum. The rate of travel of the oil through the pipe coil should be such as to permit the oil to be raised to the desired temperature without permitting the deposition of carbon in the pipes or tubes. Thus, with a coil of one inch pipe about 100 feet long, it was found advisable to force the oil through the coil at the rate of about 68 gallons per hour in the initial still of the battery, the temperature attained in the coil being about 600° F. In case the introduction of the steam or water into the coil, as through pipe 18, is found to impart too high a velocity to the stream of oil, the amount of steam or water added at this point may be decreased and additional steam or water supplied directly within the drum.

The unvaporized oil entering the drum forms a pool or body of oil therein, the movement of which is slower than that of the oil in the coil. The heat imparted to the drum is sufficient to substantially maintain the oil therein at a constant temperature while the vapors of the distillates are evolved therefrom, the initial heating of the oil

having been effected at a rapid rate in its passage through the coil in the more highly heated portions of the setting. If the proportion of vaporized oil is relatively small the heat imparted to the drum may be correspondingly reduced, and in some cases it may be unnecessary to heat the drum. It is readily apparent that the drum may be mounted upon a separate setting and may be independently heated, if desired.

Although in the example specifically set forth the use of sub-atmospheric pressure has been described, it is readily apparent that such use is not necessary to the operation of the process, which may, if desired, be carried out under atmospheric pressure. In operating a battery of stills, the temperature of treatment in the initial still and the difference in temperature between successive stills may be varied in accordance with the characteristics of the oil under treatment.

I claim:

1. The method of distilling substantially water-free oil which comprises rapidly heating the oil to bring it to a temperature at which certain of its components are normally vapors, discharging the oil into a chamber in which a body of the oil is maintained at a point above the level of the said body of oil, supplying sufficient heat to said chamber to substantially maintain the attained temperature of the body of oil, causing the incoming oil to travel through a tortuous path in the vapor space of the chamber before entering the body of oil, 100 causing the vapors evolved from the oil to travel in counter-current to the entering oil and withdrawing said vapors from the chamber.

2. The method of distilling substantially water-free oil which comprises rapidly heating the oil to bring it to a temperature at which certain of its constituents are normally vapors, discharging the oil into a chamber in which a body of the oil is maintained at a point above the level of the body of oil, supplying additional heat to the oil in said chamber, causing the incoming oil to travel through a tortuous path in the vapor space in the chamber before entering the body of oil, introducing steam into said body of oil, causing the vapors evolved from the oil to travel in counter-current to the entering oil and withdrawing vapors from the chamber.

3. The method of distilling substantially water-free oil which comprises flowing the oil in a confined stream through a highly heated zone to bring it rapidly to a temperature at which certain of its components are normally vapors, introducing an inert gaseous material into the stream of oil, discharging the stream of oil into a chamber in which a body of the oil is maintained at a point above the level of the

body of the oil, causing the incoming oil to travel through a tortuous path in the vapor space of the chamber before entering the body of oil, supplying heat to the oil in said chamber, causing the vapors evolved from the oil to travel in counter-current to the entering oil and withdrawing said vapors from the chamber.

4. The method of distilling substantially water-free oil which comprises continually flowing the oil in a confined stream through a highly heated zone to bring it rapidly to a temperature at which certain of its components are normally vapors, introducing an inert gaseous material into the stream of oil, discharging the stream of oil into an enlarged chamber above the level of the body of the oil maintained therein, causing the incoming oil to travel through a tortuous path in the vapor space of said chamber before entering the body of oil, heating said body of oil and supplying additional inert gaseous material thereto, withdrawing vapors from said chamber and withdrawing oil from the body of oil therein.

5. The method of distilling substantially water-free oil which comprises continually flowing the oil in a confined stream through a highly heated zone to bring it rapidly to a temperature at which certain of its components are normally vapors, introducing an inert gaseous material into the stream of oil, discharging the stream of oil into an enlarged chamber above the level of the body of the oil maintained therein, causing the incoming oil to travel through a

tortuous path in the vapor space of said chamber before entering the body of oil, heating said body of oil and supplying additional inert gaseous material thereto, withdrawing vapors from said chamber, withdrawing oil from the body of oil therein and subjecting the oil withdrawn to a like treatment.

6. In apparatus for the distillation of oils, a setting, a drum mounted thereon, a coil within said setting below the drum and opening into the drum in the upper portion thereof, means for forcing oil through the coil into the drum, means for introducing an inert gaseous material into the coil, means for withdrawing vapors from the upper portion of the drum, means for withdrawing oil from the lower portion of the drum and means for supplying an inert gaseous material in the lower portion of the drum.

7. In apparatus for distilling oils, a drum, a coil discharging into the upper part of the drum, means for forcing oil through the coil into the drum, means for withdrawing oil from the lower portion of the drum, means for withdrawing vapors from the upper portion of the drum, baffles arranged in the upper portion only of the drum whereby the incoming oil and the outgoing vapors are caused to travel in tortuous paths in counter-current to each other and means for supplying a heating fluid first to the coil and then to the drum whereby the coil is maintained in a more highly heated zone than the drum.

FRANK A. HOWARD.
